UNITED STATES PATENT OFFICE.

CHARLES H. HAESELER, OF PHILADELPHIA, PENNSYLVANIA.

CONDIMENT DISPENSER OR CONTAINER.

1,423,322.

Specification of Letters Patent. Patented July 18, 1922.

Application filed March 25, 1922. Serial No. 546,677.

To all whom it may concern:

Be it known that I, CHARLES H. HAESELER, a citizen of the United States, residing in the city and county of Philadelphia, State 5 of Pennsylvania, have invented a new and useful Condiment Dispenser or Container, of which the following is a specification.

My invention comprehends a novel construction of a condiment dispenser or container.

It further comprehends a novel condiment dispenser, wherein a novel construction of a cover is employed, which is secured to the body portion or casing of the dispenser in 15 a novel manner.

It further comprehends a novel valve mechanism which contributes in a novel manner to secure the cover in position.

It further comprehends novel means for 20 sealing the valve spring so that it will not be subjected to the deleterious action of the condiment being dispensed.

Other novel features of construction and advantage will hereinafter more clearly appear in the detailed description.

For the purpose of illustrating my invention, I have shown in the accompanying drawings a typical embodiment thereof which is at present preferred by me, since it 30 will give in practice satisfactory and reliable results, although it is to be understood that the various instrumentalities of which my invention consists can be variously arranged and organized and that my invention is not 35 limited to the precise arrangement and organization of these instrumentalities as herein shown and described.

Figure 1 represents, in sectional elevation, a condiment dispenser embodying my invention.

Figure 2 represents a section on line 2—2 of Figure 3.

Figure 3 represents a bottom plan view of the cover in detached position.

Figure 4 represents a top plan view of the casing with the cover and valve mechanism removed.

Figure 5 represents a bottom plan view of a cross bar employed.

Figure 6 represents, in section, another embodiment of my invention.

Similar numerals of reference indicate corresponding parts.

Referring to the drawings.

1 designates the body portion or casing of

a condiment dispenser, embodying my invention. The casing in proximity to its lower end is provided with a reduced neck 2, which merges into the outwardly flaring bottom portion 3.

The casing is provided with a chamber 4 to receive the condiment to be dispensed.

The top wall of the casing 1 is provided with the recesses 5 which are adapted to receive the ends of the cross bar or valve 65 stem guide 6, the end walls of such cross bar being shaped to conform to the recesses 5 and preferably being curved, as is understood by reference to Figures 4 and 5 of the drawings.

The cross bar 6 is provided with the upwardly extending annular flange 7. The lower portion of this flange 7 is of enlarged diameter, as indicated at 9. The cross bar 6 has depending from it a boss 10 having a 75 polygonally shaped aperture 8 and it is provided on its bottom with the ribs 11 which may or may not be arranged in parallelism, as shown in Figure 5.

12 designates the cover, which preferably 80 curves downwardly and outwardly, and then extends downwardly, and at its free end is deflected upwardly, as indicated at 13 in order to secure in position the plate 14, which, as shown, is in the form of a disc 85 having an aperture 15 of such dimensions that the disk will closely engage the outer periphery of the enlargement 9.

A portion of the metal of the plate 14 may be punched out to form the downwardly and laterally extending locking tongues 16, which are preferably resilient, as the plate 14 is preferably formed of spring metal, although it may be formed of other materials if desired.

17 designates a valve which is provided with a conical seating portion 18 which engages the valve seat 19. The upper face of the valve preferably inclines downwardly and outwardly, as indicated at 20. The 100 valve 17 is provided with a threaded aperture 21 which opens through its top but is closed at its bottom. This threaded aperture 21 is adapted to receive the lower threaded end of the valve stem 22, which is 105 polygonal in cross section and is provided with a head 23 having depending therefrom the annular flange 24, into which the flange 7 of the cross bar 6 is adapted to telescope.

The cover 12 is provided with an aperture 110

26 in which the flange 24 has a working fit.

27 designates a spring which is concealed within the chamber formed between the flanges 8 and 24. The upper end of the 5 valve stem is preferably recessed to receive an insert 30, which may have a definite color or other mark so that it will be indicative of the condiment in the dispenser.

In devices of this character, certain of the 10 condiments have a deleterious action on the metal of which the dispensers are made and for this reason, I preferably coat the wall of the chamber 4 with a material 28 such as, for example, an enamel, which if desired 15 may extend from the top wall of the chamber 4 over the valve seat 19, and also, if desired, down the inner wall of the flaring portion 3 which forms the base of the dispenser.

This material may be readily sprayed on 20 the surface to be covered by means of an air brush, or if desired it may be mechanically applied in any desired manner.

I may also, if desired, apply to the outer 25 wall of the casing a coating 29 which may be of the same character as the inner coating 28 or may be different therefrom.

The cross bar 6 may have a working fit 30 in the recesses 5, or it may be loose therein, but in practice I prefer to have the cross bar 6 fit tightly in the recess 5.

The valve stem, as illustrated, is rectangular in transverse section, and has a working fit in the aperture 8 which is also rectangular in cross section.

35 The manner in which the condiment dispenser is actuated will now be readily apparent and is as follows:—

Assuming that it is to be filled with condiment, the cover is given a partial rotation 40 to disengage the locking tongues 16 from the ribs 11, whereupon the cover can be removed and the chamber 4 filled with the desired character of condiment, such as for example salt or pepper. The cover is then replaced 45 on the casing and given a partial rotation, whereupon the locking tongues 16 will pass over the ribs 11, and the cover will be secured with respect to the cross bar and to the casing.

50 When the cover is in position, the openings made by forming the tongues 16 will be covered by the cross bar and thus prevent the passage of the condiment into the chamber between the plate 14 and the cover 12 55 and also into the chamber within which is contained the spring 17.

If the cross bar 6 is not fixed to the casing, it will be apparent that the spring 27 will contribute to resiliently secure the cover 60 to the casing.

If at any time it is desired to remove the valve, all that it is necessary to do is to unscrew it from its valve stem, whereupon the valve stem and spring can be removed if 65 desired.

If a threaded connection is made between the casing and the cover, the difficulty of imparting the proper finish to the outer wall of the casing is materially increased owing to the extra expense incurred in buffing and 70 polishing the portion in proximity to the threads, and the cost of making the threads also incurs additional expense in the manufacture. The casing is preferably made by a die casting operation. After the plate 75 14 is inserted into position, the lower portion of the cover is deflected upwardly, as at 13, in order to retain such plate 14 in assembled position with respect to the cover.

When the user desires to obtain condiment from the dispenser, he exerts the pressure of his thumb or finger on the top of the valve head stem 23 against the tension of the spring 27, whereupon the valve 17 will be moved away from its valve seat and the condiment will pass from the dispenser in a thin annular stream which diverges outwardly owing to the contour of the valve 80 and of the inner wall of the lower end of the dispenser.

When the pressure of the finger or thumb 85 of the user on the valve head stem 23 is released, the spring 27 will effect the closing of the valve 17.

The condiment is effectively prevented 90 from coming into contact with the valve operating spring and if a coating is not employed the condiment will have a deleterious action on the dispenser, so that after a limited use it will have to be thrown away 95 100 or replaced.

My present invention has been found in 105 practice to give marked and advantageous results over prior devices of this character, with which I am familiar and can be advantageously employed in the dispensing of any condiment or any other material in a comminuted condition.

It will be understood that the casing can be made of any desired material, and the 110 coating if employed is of such nature that it will render the casing impervious to moisture. Such type of coating will render a metal casing non-oxidizable as well as impervious to moisture. In other words, the 115 type of coating employed is not affected by the condiment or other material in the container.

It will now be apparent that I have devised a novel and useful construction of a 120 condiment dispenser or container, which embodies the features of advantage enumerated as desirable in the statement of the invention and the above description, and while I have, in the present instance, shown 125 and described a preferred embodiment thereof which will give in practice satisfactory and reliable results, it is to be understood that this embodiment is susceptible of modification in various particulars with 130

out departing from the spirit or scope of the invention or sacrificing any of its advantages.

Having thus described my invention, what I claim as new and desire to secure by Letters Patent, is:

1. A condiment dispenser comprising a casing having an open end, a cross bar carried at said open end, a cover, and a disc 10 closing one end of said cover and having means to lock with said cross bar to secure the cover with respect thereto.

2. A condiment dispenser comprising a casing having a discharge port at one end 15 and its opposite end open, a cross bar loosely seated on said casing at its open end, a valve stem guided in said cross bar, a valve on said stem controlling said discharge port, a cover through which said valve stem 20 passes, a plate carried by said cover adapted to interlock with said cross bar and seal

the open end of said casing, and a spring for said valve which also contributes to retain said cross bar in seated position.

3. A condiment dispenser, comprising a 25 casing having a discharge port at one end and its opposite end open, a cross bar at the open end having a sleeve, a valve stem guided in said cross bar, having a sleeve in telescopic relationship with the cross bar 30 sleeve, and contributing with it to form a chamber, a spring in said chamber, a cover through which the valve stem passes, a plate carried by said cover adapted to interlock with said cross bar and seal the open end of 35 said casing, and a valve for said valve stem controlling said discharge port.

CHARLES H. HAESELER.
